FLEXIBLE SUPPORT FOR ARTIFICIAL LEGS

Stanley J. Dew, Toronto, Ontario, Canada

Application November 18, 1943, Serial No. 510,727
In Canada October 13, 1943

6 Claims. (Cl. 3—11)

This invention relates to flexible supports for artificial legs.

Up to the present time it has been generally the practice to support artificial legs by using on the leg a metal fitting hinged at the top of the leg and curved to coincide with the shape of the body, the said metal fitting being connected with a belt and/or connected with a shoulder harness. This type of support has several disadvantages. In one case it is apparent that the rigid iron fitting disposed adjacent the hip and pivoted at one point at the side of the leg restricts the movement of the wearer of the leg. He must always bend the leg at the hip in accordance with the relatively fixed single pivot point whereas in sitting down he must sit in a particular position otherwise the metal fitting tends to dig into the body and render the wearer of the leg uncomfortable. Apart from this such a fitting restricts the natural movement of the leg, making it difficult to bend the knee in any substantially natural manner and prevents the wearer of the leg from moving the leg sidewise such as across the other leg or away from the other leg in a lateral direction. This is so because the rigid metal fitting necessarily restricts movement in either such direction.

The use of shoulder harness places considerable burden on the wearer inasmuch as the harness tends to shift with different movements of the body and imposes considerable strain on the wearer, apart from the disadvantages outlined in respect to the metal fitting. It is therefore obvious that the methods of support for artificial legs hitherto employed are open to considerable improvement.

The disadvantages outlined are entirely eliminated according to the present invention. It is, therefore, an object of the present invention to provide a movable support for artificial legs which eliminates rigid fittings and permits as near the normal operation of the leg as is possible.

A further object of the invention is to eliminate any necessity for shoulder harness in supporting a leg of this character.

A still further object of the invention is to provide a flexible support for artificial legs which may be carried entirely by a simple belt, if desired, employing a flexible yielding connection between the belt and the leg such that the wearer may act normally without requiring to move in a restricted manner as dictated by fixed points of mounting.

With these and other objects in view the invention generally comprises flexible means interposed between the artificial leg and an anchoring point on the body of the wearer permitting relatively free movement of the artificial leg in all directions.

The invention will be readily understood by reference to the following detailed specification taken in conjunction with the accompanying drawing.

In the drawing:

Fig. 1 is a perspective view of the improved flexible supporting means for artificial legs schematically illustrating the connection between an anchoring member and the leg, the latter being shown fragmentarily.

Fig. 2 is a perspective view of the flexible supporting means when mounted and viewing the wearer from the rear.

Referring to the drawing, A indicates the artificial leg and B indicates a suitable belt worn by the wearer and designed to snugly fit his hips. At spaced apart points around the belt B, pulleys 10, 11, 12, 13 and 14 are mounted. Correspondingly adjacent the top of the leg pulleys 15, 16, 17, 18 and 19 are mounted and located preferably to one side of the corresponding pulley on the belt B. Pulley 19 is preferably located at a point below the level of the pulleys 15—18.

A flexible connecting member C is designed to be threaded through the series of pulleys as shown so that it will ride over the pulleys 10—14 and under the pulleys 15—19. The free ends of the flexible connecting member C are designed to be connected together after being threaded through the system of pulleys and they are connected in a manner such that they may be detached from one another. This may be accomplished in any suitable way and in the present illustration a snap hook 20 and ring 21 are illustrated for this purpose.

Moreover, the connection between the ring 21 and/or the snap hook 20 may be made with the flexible connecting member in an adjustable manner so that if desirable the length of the flexible member in respect to its supporting characteristics may be valid. It is, therefore, apparent that the flexible member is subject to adjustment.

When the flexible connecting member is mounted in its proper position as shown particularly in Fig. 1 the leg A is firmly pulled and held in position on the stump and, subject to any possible slight stretching of this flexible member which can be taken care of by adjustment, this member will always function to hold the leg in its

proper position. Moreover, as is clearly evident merely from a consideration of the drawing, any movement of the artificial leg will result in a corresponding shifting of the flexible connecting member C as it will readily respond to such movement and move around the mounting pulleys. Therefore, if the wearer desires to raise the artificial leg forwardly by bending at the hip it is clearly evident that any pull on the flexible connector C effected, for instance, from the point of mounting of pulley 19, will result in the cable merely shifting accordingly in a natural manner around the various pulleys to compensate for the change in position of the limb from that shown in Fig. 1 to the new position. Moreover, the shifting of the member C will be to a greater or lesser degree in accordance with the degree of movement of the artificial leg. Furthermore, when the wearer sits down thus varying the position of the artificial leg from normal upright position substantially to its greatest degree, this shift of the connecting member C will permit the change in any easy natural manner. Likewise, movement of the leg laterally to the right or to the left will be compensated for naturally in substantially the same way.

The pulleys in some instances are positioned at different levels. For instance, the pulley 19 is positioned at a point substantially lower on the leg A than the pulleys 15-18 in order to increase the leverage. On the other hand, it is preferable to position the intermediate pulleys 11, 12 and 13 on the belt B slightly lower and substantially on a grade as this lends to a freer movement of the flexible member. Furthermore, it is preferable to have a series of five pulleys so as to provide for a suspension member C of substantial length, thus to avoid any tendency to pull when the wearer sits down which changes the position of the leg from normal upright to substantially horizontal position so far as the top portion of the leg is concerned.

While it is preferred to use pulleys thus eliminating friction on the flexible connector C and providing for easy free movement, it could be, of course, threaded through suitable guides without departing from the spirit of the present invention.

From the foregoing it is obvious that my invention provides for a free substantially natural movement of an artificial leg by reason of a simple free moving flexible support which must respond in a substantially natural manner to any movement of the leg.

What I claim as my invention is:

1. Means for attaching an artificial leg comprising in combination with an artificial leg a body encircling member, endless flexible means extending between the artificial limb and said body encircling member to hold said limb in position, and means for connecting said flexible means with said limb and body encircling member to cause a compensating shifting of said endless flexible means responsive to any movement imparted to said limb.

2. Means for attaching an artificial leg comprising in combination with an artificial leg a body encircling member, a series of members an-

chored to said body encircling member at spaced apart points and a series of members anchored adjacent to the top of the artificial leg and endless flexible means extending between the members on the body encircling member and the members on the leg to hold the leg on the stump of the wearer, said endless flexible means being free to shift around said members responsive to any movement imparted to the artificial leg to permit the latter to be freely moved.

3. Means for attaching an artificial leg comprising in combination with an artificial leg a body encircling member, a series of pulleys anchored to said body encircling member at spaced apart points and a series of pulleys anchored adjacent to the top of the artificial leg and flexible means extending between the pulleys on the body encircling member and the pulleys on the leg to hold the leg on the stump of the wearer, said flexible means being free to shift around said pulleys responsive to any movement imparted to the artificial leg to permit the latter to be freely moved.

4. Means for attaching an artificial leg comprising in combination with an artificial leg a belt member designed to encircle the hips of the wearer, a series of members anchored to said belt at spaced apart points and a series of members anchored adjacent to the top of the artificial leg corresponding in number to those on the belt and a flexible connector passing over the members on the belt and the members on the leg and connected to form an endless flexible connector suspending the leg from the belt, said flexible connector acting to hold the leg on the stump of the wearer and being free to shift around said members responsive to any movement imparted to the artificial leg, to permit the latter to be freely moved.

5. Means for attaching an artificial leg comprising in combination with an artificial leg a belt member designed to encircle the hips of the wearer, a series of pulleys anchored to said belt at spaced apart points and a series of pulleys anchored adjacent to the top of the artificial leg corresponding in number to those on the belt and a flexible connector threaded around the pulleys on the belt and the pulleys on the leg and connected to form an endless flexible connector suspending the leg from the belt, said flexible connector acting to hold the leg on the stump of the wearer and being free to shift around said pulleys responsive to any movement imparted to the artificial leg, to permit the latter to be freely moved.

6. Means for attaching an artificial leg comprising a belt member designed to encircle the hips of the wearer, a series of members anchored to said body encircling member at spaced apart points and a series of members designed to be anchored at spaced apart points on the upper portion of an artificial leg and endless flexible means threaded through both series of members to permit a free floating movement of the endless flexible means in said members when said second series of members is anchored on a leg and it is applied on the body of a wearer.
